MIXING DEVICE

Paul Louis Armand Thiberge, Nanterre, France

Application August 9, 1933, Serial No. 684,466
In France September 9, 1932

6 Claims. (Cl. 259—5)

The present invention relates to mixing devices for mixing and emulsifying together two or more bodies of the type in which said bodies are caused to pass between balls or similar organs 5 rolling between a stationary part and a rotary part.

The mixing or emulsifying of these bodies, which may be either all in the liquid state or some in the liquid and others in the solid or gaseous state, is due to the vertical motion imparted to said bodies or constituents as they are being caused to pass between the movable walls of the channels formed by the intervals existing between the balls.

15 It is an essential condition that the dimensions of these channels should be adapted to the nature of the bodies or constituents to be mixed or emulsified together and also to the degree of dispersion to be obtained.

20 For instance, in the refining of petroleum derivatives, it is necessary to more or less disperse the reagents that are employed (among which sulfuric acid is present according to the results to be obtained.)

25 The refining will therefore be the easier as the mixing apparatus is better adapted to variations in the degree of dispersion.

According to my invention, the surfaces along which the balls are rolling are given convergent profiles in order that the balls, freely poured onto them, may be applied against them merely through the action of their weight and of the centrifugal force that is developed by their rotation.

35 Under these conditions, when the machine is not running, it is easy to remove the balls and to replace them by balls of a different diameter.

Furthermore, the fact that the pressures supported by the balls and by the surfaces along 40 which they roll are reduced to those resulting from the weight of the balls and of the centrifugal force acting upon them permits a much wider choice of the materials that may be utilized for the construction of the mixing machine.

45 If for instance the mixture or emulsion contains a more or less corrosive constituent, it is possible to make the balls and the surfaces along which they roll of a material capable of withstanding without injury the corrosive action of said constituent but the resistance of which to compression is low.

Preferred embodiments of the present invention will be hereinafter described with reference to the accompanying drawing, given merely by way of example, and in which:

Fig. 1 is a diagrammatical sectional view of a first embodiment, taken in a plane passing through the axis of the apparatus;

Fig. 2 is a similar view of another embodiment;

Fig. 3 is a similar view of still another embodiment;

Fig. 4 is a similar view of a variation of the embodiment of Fig. 3.

In the embodiment of Fig. 1, the movable surface along which the balls are caused to roll 10 consists of a disk 1 coaxially disposed with respect to the vertical shaft 1 that supports it. The stationary surface along which the balls are caused to roll consists of the inner wall of a ring 3 coaxially disposed with respect to the disk. The 15 profile of the last mentioned surface is at right angles to the surface of disk 1.

The balls 4, which are poured in bulk onto disk 1, automatically distribute themselves along the inner face of ring 3, against which they are 20 applied by the action of the centrifugal force resulting from the movement of the balls about the axis of shaft under the effect of the rotation of disk 1. The constituents to be mixed or emulsified together are admitted at the upper portion 25 of ring 3 and the mixture of emulsion obtained is discharged between the periphery of disk 1 and the lower inner edge of ring 3.

In the embodiment of Fig. 2 the inner profile of ring 3 is given an inclination such that the 30 distance between said disk and the upper face of disk 1 decreases as the distance from the axis of shaft 2 increases.

In the embodiment of Fig. 3, the upper face of disk 1 is given the shape of a cone the angle at 35 the apex of which is very large. The inner face of ring 3 is given the shape of a frustum of a cone the angle at the apex of which is smaller than that just above mentioned. It results therefrom that the distance between the upper 40 face of disk 1 and the inner face of ring 3 decreases in proportion to the distance from the axis of shaft 2, or, in other words, decreases in a continuous manner from the central portion of disk 1 to the periphery thereof; consequently, in 45 devices of the types of those shown in Figs. 2 and 3, the balls settle at a distance from the axis of shaft 2 that varies according to their diameter.

The same is true of the embodiment of Fig. 4, which comprises a rotary plane disk 1 cooperating with a ring 3 the cross section of which 50 comprises a series of steps which are the nearer to the surface of disk 1 as they are farther from the axis of shaft 2.

The embodiments of Figs. 3 and 4 are well 55

adapted to the simultaneous use of balls of different diameters. These balls then form a series of concentric circular rows providing passages of gradually decreasing dimensions between them for the passage of the constituents of the mixture or of the emulsion, the velocities of the relative displacements of the walls of these passages increasing inversely to their diameters. It follows that the mixing or emulsifying takes place gradually, which may be interesting in the case of constituents that are difficult to mix or to emulsify together. This also permits of introducing the various constituents successively, at the desired phase of the mixing operation. Thus, in the embodiment of Fig. 4, two of the constituents of the mixture are admitted, through conduits 5 and 6 respectively, into the central part of the machine, while a third constituent is fed, through conduit 7 between the two circular rows of balls shown in the drawing.

While I have described what I deem to be practical and efficient embodiments of my invention, it should be well understood that I do not wish to be limited thereto as there might be changes made in the arrangement, and form of the parts without departing from the principle of my invention as comprehended within the scope of the appended claims.

What I claim is:

1. A machine for mixing together at least two fluid substances which comprises in combination two coaxial organs adapted to rotate with respect to each other about their common axis, a plurality of balls each in contact with both of these organs, and means for feeding the substances to be mixed together onto the central portion of one of said organs, the surfaces of said organs that contact said balls consisting of surfaces of revolution the respective axial sections of which are two lines converging toward their peripheries, whereby the balls are applied against said surfaces merely by their weight and the action of centrifugal force, the common axis of said surfaces being vertical with the lower surface conical and the upper surface also conical and extending in the same direction but with a smaller angle at the apex of the cone, the balls being of different sizes and automatically positioning themselves in a radial direction according to their diameter.

2. A machine for mixing together at least two fluid substances which comprises in combination two coaxial organs adapted to rotate with respect to each other about their common axis, a plurality of balls each in contact with both of these organs, and means for feeding the substances to be mixed together onto the central portion of one of said organs, the surfaces of said organs that contact said balls consisting of surfaces of revolution the respective axial sections of which are two lines converging toward their peripheries, whereby the balls are applied against said surfaces merely by their weight and the action of centrifugal force and means for feeding a substance to be mixed at an intermediate point of the radius of said organs.

3. A machine for mixing together at least two fluid substances which comprises in combination two coaxial organs adapted to rotate with respect to each other about their common axis, a plurality of balls each in contact with both of these

organs, and means for feeding the substances to be mixed together onto the central portion of one of said organs, the surfaces of said organs that contact said balls consisting of surfaces of revolution the respective axial sections of which are two lines converging toward their peripheries, whereby the balls are applied against said surfaces merely by their weight and the action of centrifugal force, said balls being of different sizes forming a plurality of circular rows and means for feeding a substance to be mixed between two of said rows of balls.

4. A machine for mixing together at least three fluid substances, which comprises in combination, two coaxial organs adapted to rotate with respect to each other about their common axis, the respective surfaces of said organs that face each other consisting of surfaces of revolution the respective axial sections of which are two lines converging toward the periphery, a set of balls of a given diameter arranged to be in contact with both of these surfaces, at least another set of balls of a different diameter arranged to be also in contact with both of these surfaces, means for feeding two of the substances to be mixed together onto the central portion of one of these organs, and means for feeding a third substance to be mixed with the two first mentioned ones between the sets of balls of different diameters.

5. A machine for mixing together at least three fluid substances, which comprises in combination, a rotary plate, an organ mounted above said plate in coaxial relation therewith adapted to rotate with respect thereto, the under surface of this organ that is located opposite the upper face of said plate consisting of a surface of revolution the axial section of which is a line converging toward the periphery of said plate, a set of balls of a given diameter resting on said plate so as to be in contact with said surface of revolution, another set of balls of a different diameter resting on said plate so as to be also in contact with said surface of revolution, means for feeding two of the substances to be mixed together onto the central part of said plate, and means for feeding a third fluid substance to the two first mentioned ones between the sets of balls of different diameters.

6. A machine for mixing together at least three fluid substances, which comprises in combination, a rotary plate, an organ mounted above said plate in coaxial relation therewith adapted to rotate with respect thereto about their common axis, the under surface of said organ that is located opposite the upper face of said plate consisting of a surface of revolution the axial section of which is a stepped line converging toward the periphery of said plate, a set of balls of a given diameter resting on said plate so as to be in contact with said surface of revolution along a step thereof, another set of balls of a different diameter resting on said plate so as to be in contact with said surface of revolution along another step thereof, means for feeding two of the substances to be mixed together onto the central part of said plate, and means for feeding a third fluid substance to the two first mentioned ones between the sets of balls of different diameters.

PAUL L. A. THIBERGE.
